Primary Examiner — Mark Goodwin*(74) Attorney, Agent, or Firm* — Carrithers Law Office PLLC(57) **CLAIM**

The ornamental design for a tie down, as shown and described.

DESCRIPTION

FIG. 1 is a perspective view of an tie down showing my new design;

FIG. 2 is a front plan view thereof;

FIG. 3 is a rear plan view thereof;

FIG. 4 is a left side view thereof;

FIG. 5 is a right side view thereof;

FIG. 6 is a bottom plan view thereof; and,

FIG. 7 is a top plan view thereof.

The broken lines shown in the drawings represent portions of the tie down that form no part of the claimed design.

1 Claim, 2 Drawing Sheets(56)
